UNITED STATES PATENT OFFICE

JACOB M. OLINGER, OF SPRINGFIELD, OHIO

BURNER

Original application filed February 17, 1926, Serial No. 88,753. Divided and this application filed May 25, 1929. Serial No. 366,014.

My invention relates to improvements in burners for gas heating stoves, this application being a division of my pending application Serial No. 88,753, filed February 17th, 5 1926, which has matured into Patent No. 1,719,994, dated July 9th, 1929.

The object of the invention is to provide a burner and mixer for the fuel of a character particularly adapted for a stove of the peculiar 10 design set forth herein.

In the accompanying drawings:

Fig. 1 is a front elevation of a stove embodying my improvement.

Fig. 2 is a side elevation of the same.

Fig. 3 is a sectional view on the line 3—3 of Fig. 1.

Fig. 4 is a sectional view on the line 4—4 of Fig. 3.

Fig. 5 is a detail plan view of the burner, 20 mixing chamber and mixing valve.

Referring to the drawings, 1 represents the base of the stove of curved form. The rear ends of this base are connected to vertical standards 2 and the forward portion of the base is provided with a pair of supporting legs 3. Secured to the base 1 and by the standards, is a support for the heating elements. This support consists of a curved shaped portion 5, concavo-convex in cross section, an inner projecting shelf 6, an intermediate shelf 7 and a rear cross bar 8. The intermediate shelf 7 forms a support for a series of heat elements 9, which are known as radiants, while the shelf 6 forms a support 25 for a curved back wall 10 of fire-proof material. This back wall 10 has at its upper end an integrally formed overhanging portion 10', the forward edge of which is of curved form. The radiants 9 are formed of fire-proof material and are of a type well known in the art of gas heating stoves. These radiants are held in position by a flange 5' formed at the juncture of the portion 5 and shelf 7 and also by a groove formed on the under 30 side of the portion 10', as indicated in dotted lines at 10''. The fire back 10 is held in position by forming therein grooves 11, which grooves engage the inner projecting edges of the standards 2 as shown in Fig. 3.

As clearly shown in Figs. 3 and 4 a jacket

plate 20 of usual form is secured to the rear faces of the uprights 2, and by reason of the particular connection of the ends of the substantially semi-cylindrical fire-back 10, no portion of the fire-back contacts with the jacket plate, the space between the fire-back 10 and jacket plate 20 providing for circulation of air therebetween so the stove may be set close to a house wall without danger of setting fire to the same due to the heat radiating 55 from the fire-back, when the stove is in use. A cap 4 of ornamental appearance is laid on the overhanging portion 10' of the fire wall, the upper end of the jacket plate 20 and on the upper ends of the standards. 60

The curves upon which the support, back wall, and overhanging portion are formed are such that the radiants at each end of the series are located on the arc of a circle of smaller radius than that of the intermediate 65 radiants.

The burner which I employ consists of a forwardly disposed chamber 12, disposed in a curvilinear direction corresponding to that of the radiant support, a rear chamber 13, 70 two hollow arms 14 connecting the two chambers, a hollow member 15 connected at its rear end with the chamber 13, and a fuel and air mixing valve 16 connected with the forward end of the member 15. The chambers 75 12 and 13 and the arms 14 are preferably integrally formed while the member 15 is bolted to the flanged open bottom of the chamber 13. The burner thus formed is connected with ears 17, projecting from the rear edge 80 of the shelf 6, and is also fastened to the standards 2 and to bosses formed on its rear side of the cross-bar 8. The chamber 12 is disposed beneath the radiants 9 and is provided with a series of nozzles 18, one for 85 each radiant, which are screwed into openings 18' in the upper wall of the chamber 12. It will be noted that the passage in the member 15 diverges toward the mixing chamber, 90 while the passages in the members 14 converged from the chamber 13 to the chamber 12. This allows the air and gas to enter the mixing chamber in an expanded condition to secure a more thorough mixture, and to 95 be then again contracted before entering the 100

burner chamber 12 to give it the proper density for efficient combustion.

Having thus described my invention, I claim:

- 5 1. In a burner for a gas heating stove of the type which has a series of exposed heating elements arranged in the open front of the stove in a curvilinear series, with the elements at each end of the series arranged on the arc of a circle of shorter radius than that of the intermediate elements, the combination of a burner member having a chamber arranged beneath said heating elements extending in a curvilinear direction with the ends thereof each formed on the arc of a circle of shorter radius than the intermediate portion thereof to conform to the curvature of the heating elements, and a plurality of nozzles carried by said chamber, one for each heating element.
- 10 2. In a burner for a gas heating stove of the type which has a series of exposed heating elements arranged in the open front of the stove in a curvilinear series, with the elements at each end of the series arranged on the arc of a circle of shorter radius than that of the intermediate elements, the combination of a burner member consisting of a rear chamber, a forward chamber, said forward chamber being arranged beneath said heating elements extending in a curvilinear direction with the ends thereof each formed on the arc of a circle of shorter radius than the intermediate portion thereof to conform to the curvature of the heating elements, and a pair of communicating passageways extending from said rear chamber to said forward chamber, and means for supplying a mixture of gas and air to said rear chamber, and a plurality of nozzles carried by said forward chamber, one for each heating element.
- 15 3. In a burner for a gas heating stove of the type which has a series of exposed heating elements arranged in the open front of the stove in a curvilinear series to present a convex heating surface, the combination of a burner consisting of a rear chamber, a forward chamber, said forward chamber being arranged in a curvilinear direction beneath said heating elements and being considerably less in length than an endless structure of the same curvature and having its ends closed, a pair of communicating passageways extending from said rear chamber to said forward chamber, a gas supply passage extending rearwardly in communication with said rear chamber, and a gas and air valve connected with said last mentioned passageway and located adjacent the forward portion of the stove.
- 20 4. In a burner for a gas heating stove of the type which has a series of exposed heating elements arranged in the open front of the stove in a curvilinear series to present a convex heating surface, the combination of a

burner consisting of a rear chamber, a forward chamber, said forward chamber being arranged in a curvilinear direction beneath said heating elements, a pair of communicating passageways extending from said rear chamber to said forward chamber, said passageways diverging from said rear chamber to said forward chamber and forming communications between said chambers, each of said passageways being converged from the rear chamber to the forward chamber, a fuel supply diverging passageway leading to said rear chamber, and a gas and air valve controlling said last mentioned passageway and located adjacent the forward portion of the stove.

In testimony whereof, I have hereunto set my hand this 24th day of May, 1929.

JACOB M. OLINGER.
